(57) **CLAIM**

The ornamental design for a miniature golf hole, as shown and described.

DESCRIPTION

FIG. 1 is a front perspective view of a miniature golf hole according to our new design;

FIG. 2 is a front view thereof;

FIG. 3 is a rear view thereof;

FIG. 4 is a top plan view thereof;

FIG. 5 is a side elevational view thereof;

FIG. 6 is an opposite side elevational view thereof;

FIG. 7 is a top front perspective view thereof;

FIG. 8 is a top rear perspective view of FIG. 7; the circular disc elements being shown in an alternate position; and,

FIG. 9 is a front perspective view of FIG. 1; the circular disc elements being shown in another alternate position.

The broken lines in the figures show portions of the miniature golf hole that form no part of the claimed design.
